UNITED STATES PATENT OFFICE.

OSROE A. CLARK, OF NEWARK, NEW JERSEY.

RAZOR.

1,274,139.

Specification of Letters Patent.

Patented July 30, 1918.

Application filed October 26, 1916. Serial No. 127,818.

To all whom it may concern:

Be it known that I, OSROE A. CLARK, a citizen of the United States, and a resident of Newark, county of Essex, and State of New Jersey, have invented certain new and useful Improvements in Razors, of which the following is a specification.

This invention relates to a razor which is of the type that employs removable blades, these blades being usually made of thin material for which reason they are cheap to make, and the blades are adapted to be destroyed and thrown away and replaced by a new blade when it is necessary. 10 The razor is of this kind and is provided with a holder for the blade, which holder permits a ready insertion of the blade longitudinally so that there is no danger of cutting the hands in inserting the blade, 15 the blade when in place being firmly held in position by reason of the holder being constructed so as to extend upward along the thin blade to make it rigid enough so that it does not vibrate when used for shaving, the holder also having its end constructed so that it yieldingly resists any longitudinal outward movement of the blade, in this way preventing accidental 20 sliding of the blade in the holder. 25 The holder is furthermore improved in that it has a means for engaging the blade to permit the blade being slid with its outer end beyond the outer end of the holder so that it can be grasped for its complete withdrawal, this initial or starting movement of the blade being thus made safe by preventing the cutting of the fingers in the removal of the blade, such expelling means being 30 preferably placed so that the handle portion, providing for its manipulation, projects from the rear or back edge of the holder.

The invention also consists in minor improvements to be more fully described hereinafter and which are also embodied in the clauses of the claim.

The invention is illustrated in the accompanying drawing, in which Figure 1 is a perspective view of the improved razor. 50 Fig. 2 is a view enlarged over the size shown in Fig. 1, this figure being partly broken away to more clearly illustrate the interior construction and embodying one type of holder with the blade in position, the blade also being shown in dotted outline in the 55 position it assumes when partly expelled

from the holder. Fig. 3 is an end view of Fig. 2, and Fig. 4 is a section on line 4—4, in Fig. 2. Fig. 5 is an enlarged top view of the left end of that part of the razor 60 illustrated in Fig. 2.

In Fig. 1 I show the razor provided with the usual form of handle 10 to which is pivoted the holder of the blade, the holder being usually made by folding over a strip 65 of metal, the folded over portion forming cheek-pieces 11 which go to make up the shank of the holder, which shank is pivoted, as at 12, to the handle 10 so that the holder can be swung into the space between 70 the sides of the handle, as is usual in razors. The cheek-pieces 11 are preferably integral with the projecting leaves 13 which are folded over from the back 14 and are preferably made with a considerable space between them so as to permit the insertion of a blade that has a stiffening backing on its rear end. The leaves 13 are provided with jaws 15, these jaws being somewhat close together, being usually made a trifle closer 75 together than the width or thickness of the blade to be employed, so that they grasp a blade by their spring action, the holder being preferably made of metal having a slight spring action to permit the automatic 80 grasping of the blade. The blade 16 has a cutting edge 17 and is generally provided with a backing 18 which consists of a folded strip of metal heavier than the blade so that the blade does not bend longitudinally 85 and can be much more easily handled when it is to be stropped or sharpened. The outer end of the holder is open, through which open end the blade is inserted and withdrawn, and adjacent to said open end the 90 outer ends of the jaws, as at 19, are constructed so that they form a smaller space between them than the normal distance between the jaws in order to form a yielding means to prevent the withdrawal of the 95 blade by accident, and to prevent the movement of the blade in the holder during the act of shaving. In the drawing this reduction of interval between the ends of the jaws is provided for by bending the outer ends 100 19 of the jaws slightly toward each other, as will be clearly seen from Figs. 3 and 5. In other words, when the blade is in position the outer edge 20 of the blade passes within the pinched or bent ends 19 of the 105 jaws and the jaws have a "bite" which securely holds the blade in position.

In order to permit sliding of the blade to a position where it is thus held, the jaws are cut away as at 21 to provide a finger space so that the finger can still engage the end 20 5 of the blade or the end 22 of the backing 18 when the blade arrives at its proper position in the holder, that is, with its outer edge beyond the turned ends of the jaws.

The shank is preferably provided with a 10 filling block 23 which is secured between the cheek-pieces 11 and thus provides, with said cheek-pieces and the back edge 14 of the holder, a channel in which a slide 24 is placed, the slide having a longitudinal path 15 of travel and being adapted to be manipulated from the outside, one means being in the form of a finger-piece 25 which projects through the slot 26 in the back of the holder. The slide is disposed so that the distance between the front edge 27 of the slide and a 20 point slightly within the bent ends 19 of the jaws is no less than the length of the blade 16 or of its backing. In this way the blade is insured against being longer than the distance 25 between the bent ends of the jaws and the forward end of the slide, and it is thus held against any longitudinal movement, any backward movement being resisted by reason of the blade abutting on the slide and 30 any forward movement being resisted by reason of the blade engaging the slightly bent ends of the jaws. When, however, it is desired to withdraw the blade, the finger-piece 25 is slid forward, usually by the 35 thumb, and this slides the blade forward to the position shown in dotted outline to the left of Fig. 2, presenting the blade in a manner so that it can be grasped at a place other than near its cutting edge and can be safely 40 withdrawn from the holder. On the insertion of the blade, and to easily overcome the resistance of the ends 19 of the jaws, the blade has its outer end inclined slightly downward, the rear edge of the blade being 45 inserted first in the space between the leaves 13 and then by being swung upward and inward, the inner edge 28 of the blade enters between the ends 19 of the jaws upward and inward, the jaws being thus easily parted by 50 reason of the inner edge of the blade engaging the converging parts 29 of the leaves.

In this way the jaws are more easily parted than if an attempt was made to slide the blade, on its initial entrance, into the holder substantially parallel thereto. It will be 55 evident that the holder is stiff enough to permit the installation of any of the usual forms of guards that are placed on razors to transform them into safety razors.

It will be understood that slight changes 60 may be made in the construction without departing from the scope of the invention.

Having thus described my invention, I claim:

1. A razor comprising a blade of the wafer type, a holder into which the blade slides longitudinally, the holder having spring jaws extending so as to grasp the blade well toward its cutting edge, the jaws having their outer ends bent toward each other so 70 that the distance between them is less than the thickness of the blade, and a stop for the inner end of the blade disposed so that the blade is halted when its outer end is within the bent ends of the jaws whereby the blade 75 is firmly held between said jaws, said jaws being separated from one another a substantial distance back of said bent end portions, whereby the insertion of the end of the blade between said jaws moves said bent portions 80 of the jaws apart and permits the insertion of the wafer portion of the blade therebetween.

2. A razor comprising a blade of the wafer type, a holder into which the blade slides 85 longitudinally, the holder having spring jaws extending so as to grasp the blade well toward its cutting edge, the jaws having their outer ends bent toward each other so that the ends abut, and a stop for the blade 90 disposed so that the blade is halted when its outer end is within and in contact with the bent ends of the jaws, the ends of the jaws being cut away between the bent ends and the back of the holder to form curved converging front ends to the jaws, whereby an 95 upward initial insertion of the inner end of the blade parts said bent ends.

In testimony that I claim the foregoing I hereto set my hand this 25th day of October, 1916.

OSROE A. CLARK.
